VALVE MECHANISM FOR SERVO-MOTORS

Charles A. Butler, Okmulgee, Okla.; Sadie A. Butler administratrix of said Charles A. Butler, deceased

Application February 23, 1933, Serial No. 658,199

8 Claims. (Cl. 121—38)

This invention relates to improvements in pneumatically actuated pumping systems of the type described in my prior Patent No. 1,839,140, and in my copending applications Serial Nos. 602,348 and 602,349, filed March 31, 1932, and more particularly relates to improvements in the assemblage of such units.

One of the features of the present invention is the construction of a servo motor structure in which reciprocating valves of the needle type are employed for controlling the actuation of the servo motor piston.

Another feature of the present invention is the provision of a mechanism for actuating such reciprocating valves by which the inlet and exhaust from the opposite ends of the servo motor cylinder are positively controlled, and means are provided for holding the valves in opened or closed position.

A further feature of the invention is the provision of such a valve-controlled system, including two pairs of valves with means for balancing the efforts upon the valves while permitting them to be firmly seated for obstructing their corresponding passages.

Still another feature of the invention is the provision of sealing means at the ends of the cylinder for cooperation with the faces of the piston in securing tightness against leakage around the piston while the latter is at its ends of travel.

A still further feature of the present invention is the provision of a servo motor controlled system which is not subject to derangement or improper operation by reason of sudden air movements within the pump structure.

With these and other objects in view, as will appear in the course of the following specification and claims, an illustrative form of practicing the invention is set forth on the accompanying drawings, in which:

Figure 1a is a fragmentary upright sectional view substantially on line 1a—1a of Figure 2.

Figure 1b is a similar view substantially on line 1b—1b of Figure 3.

Figure 1c is a view corresponding to that of 1b, but showing the lower portion of the general casting.

Figure 2 is a horizontal sectional view, substantially on line 2—2 of Figure 1a.

Figure 3 is a horizontal sectional view substantially at line 3—3 of Figure 1b.

Figure 4 is an upright sectional view, on a larger scale, of the servo motor and its control system, being in section substantially on lines 4—4 of Figures 5 and 9.

Figure 5 is an upright sectional view substantially on line 5—5 of Figure 4.

Figure 6 is a fragmentary upright sectional view substantially on lines 6—6 of Figures 7 and 9.

Figures 7, 8 and 9 are horizontal sectional views through the servo motor substantially on lines 7—7, 8—8 and 9—9 of Figure 4.

Figure 10 is a detail of the valve pivot arrangement, on a larger scale than that of Figure 5.

Figure 11 is a perspective view of the valve actuator rocker-piece.

Figure 12 is a view corresponding to a portion of Figure 4, but showing the valve actuating and controlling elements in a different position.

In these drawings, a single unit for a pumping system is set out for operation as described in my aforesaid Patent 1,839,140, and in the copending applications. In the patent and applications an air pressure pipe is carried from the ground level, for instance, downwardly in an oil well casing to the lowermost pumping unit, and is provided with branch connections to each individual unit. In operation the air pressure is initially automatically shut off from the lowermost unit and this unit is permitted to fill with oil. When this lowermost unit is full, a float is raised and thereby the control valves of a servo motor are actuated to cause a movement of the servo motor piston and thus an opening of the branch connection to this air pressure pipe. At the same time, an air exhaust from this unit is closed. The entering air under pressure thus operates to force the oil from this unit upwardly through an oil delivery pipe to a next higher unit. The units are constructed similarly and thus operate in cascade to effect a raising of the oil by each successive unit until it is delivered at the ground level. A more detailed description of this operation by several units is contained in my aforesaid patent, and the employment of such a plurality of units in cascade is not claimed in the present application.

The present application is concerned with the construction of a unit for employment in such a system.

The structure is set out on the accompanying drawings as including an air connection and exhaust system of the type described, shown and claimed in the aforesaid copending application Serial No. 602,349. According to such an arrangement a conduit 10 for gas under pressure is led downward to and through the unit, if it be other than the bottom unit, so that the conduit 10 supplies the gas under pressure to all of the units. At a point above the unit, the pipe 10 has a

branch 116 communicating with the branch conduit 13 through which air may pass to a back pressure valve 126 and thus through the passage 7 in the upper closing plug 18 to the air inlet valve 45 of the unit. Likewise, the upper closing plug 18 has a passage 26 therein for establishing communication from the exhaust valve 32 to the exhaust pipe 26a which extends upwardly from the closing plug 18 any desired distance, and is preferably provided at its upper end with a check valve structure 137b which will prevent the downward movement of fluid in the exhaust pipe 26a.

Likewise, the unit is shown as including a casing 19 having a bottom closing plug 22 through which the pressure-gas conduit 18 may extend, and to which is led the supply conduit 12 by which liquid may enter the unit. The inlet pipe 12 is in communication with the body 92 of a check valve structure having a valve body 94 to prevent the reflux of liquid from the unit. A liquid discharge pipe 78 is located within the unit and is provided at its lower end with a check valve 85 which prevents the return of liquid from pipe 78 into the unit. The pipe 78 extends upwardly and communicates through the upper closing plug 18 with a liquid discharge line as described in my aforesaid patent and applications.

30 The gas inlet and outlet valves 45 and 32 are connected to corresponding slide blocks 44 and 31 which may be moved by the lever 67 which is pivotally mounted on the axially movable rod 65. This rod 65 is pivoted at its lower end to a lever 39 which is supported by a fixed pivot 40 on a fixed bar 41, at one end, and is connected by pivot 38 at the other end to the piston rod 37 of a servo motor structure. When the piston rod 38 is in raised position, the inlet valve 45 is open and the exhaust valve is closed; and vice versa when the piston rod 37 is in a lower position, the inlet valve 45 is closed and the exhaust valve 32 is open.

Within the housing 19 is provided a float 71 which is raised by the liquid when the latter has attained a predetermined level in the housing 19, and thus operates to raise a lever 54 which is supported on a fixed rod 68 and is pivotally connected to a servo motor actuating link 53, 53b, whereby it operates to move a lever arm 52 and thus, in a manner described hereinabove, to cause a movement of the servo motor parts including the piston rod 37 whereby to raise the rod 65 and thus move the valves into the position shown in Figure 1a.

Further, the casing is provided with a bucket 74 which is in part counter-balanced by a spring 82 so that it rises when the liquid level is above its top; but so that its contents of liquid will cause it to drop as the liquid level retreats, and thus ultimately depress a lever 69 which is pivotally mounted on a rod 72 and thus operate to draw the servo motor control link 53b, 53 down again. The bucket 74 is preferably mounted within a shield 75. The spring 82 and the shield 75 are supported by brackets 77 connected to the pipes 10, 78 within the housing 19. A buffer 81a is likewise supported by a bracket 81 in similar manner, and serves to receive the float 71 at the end of the downward movement of the latter. The inlet of gas under pressure to the servo motor is accomplished through a branch connection 130 from branch conduit 13, by a pipe 61; while the exhaust from the servo motor 75 is accomplished through a pipe 59 and its ex-

tension 59a which leads to a check valve 137, having the same general height above the upper closing head or plug 18 and the same function as the check valve 137b.

These parts are disclosed, with the same reference numerals, in my aforesaid copending application Serial No. 602,349, and are referred to in the present application to show the relationship of the structure here described to these prior devices.

The hollow structure 30 in which is provided the seat for the exhaust valve 32 and a sliding support for the valve block 31, serves in the present illustration also to support the threaded end 140 of a block 141 which has spaced downwardly extending arms 142 secured thereto. These arms 142 are connected, as by welding, at their lower ends to a block 143 providing the fixed body of the servo motor structure. The lower part of this body has a cavity 144 constituting a cylinder. The lower end of the cylinder is closed by a screw plug 145 through which the piston rod 37 passes, with the employment of a tight packing 146. The upper end of the piston rod 37 is reduced and receives against its shoulder the rabbetted disk 147, the flat disk 148 and the threaded and rabbetted nut member 149. These three members have substantially the same diameter and provide a piston structure in conjunction with the piston rings 150 located in the rabbet grooves. The upper end of the cylinder 144 has an annular groove in which is received a sealing ring 151 which may be of rubber or like material for cooperation with the upper surface of the closing nut 149 when the latter is in its uppermost position, so that the tightness of the piston, in this end position, does not depend wholly upon the piston rings 150.

Similarly, the plug 145 is rabbetted at its upper end to receive a sealing ring 152.

Four parallel holes are provided in the upper end of the servo motor body, the axes of these holes being parallel to the axis of cylinder 144 and piston rod 37 in the illustrated form. Each of these holes is intended to receive a longitudinally movable needle valve, and is closed at its upper end by a packing 153 for preventing the escape of compressed gas along the length of the needle valve. These needle valves are arranged in pairs, comprising an inlet valve 154a and an outlet valve 154b for the lower end of the cylinder, and an inlet valve 154c and an outlet valve 154d for the upper end of the cylinder. Each of the aforesaid holes has a large diameter down to the two diagonally extending passages 159, 161 which are respectively in communication (Figs. 5, 8 and 9) with the corresponding exhaust and inlet conduits 59 and 61. Thus, the inlet valves 154a and 154c control the movement of compressed gas from the passage 158, while the valves 154b and 154d control the movement toward the exhaust passage 159.

The aforesaid four bore holes are smaller at their lower ends, below the diagonal passages 159 and 161 which intersect therewith, and their walls 65 adjacent such diagonal passages provide seats for the lower ends of the said valves. The bore hole 155a corresponding to valve 154a leads into a cross-communicating passage 156 and thence to a longitudinal passage 157 downwardly along the 70 cylinder 144, with communication through an opening 158 with a peripheral groove 145a in the lower closing plug 145, and this groove in turn communicates by openings 145b with the internal space of cylinder 144. Into the cross pas-

sage 156 also opens the hole 155b corresponding to the valve 154b. The holes 155c and 155d are shown in this form as communicating directly with the upper end of the space of cylinder 144.

5 The lever 52 is shown in Figures 4 and 5 to be doubled in structure, and to have upwardly extending arms 52a integral therewith; these arms being connected to a block 162 providing a rest for a knife edge 163 secured at the lower end of a plunger having a collar 164 which is forced downwardly by a spring 165 resting at its upper end against the bottom of a cavity in a toggle cap 166 which has a point 166a resting in a depression 167 in the block 141. The upper ends of arms 52a are preferably provided with spaced points (Fig. 4) between which is received the knife edge 163, which for its part has downwardly extending portions at its ends for preventing translational movement of the knife edge in the direction of its length.

20 The lever 52 is connected by a pivot 170 with a valve member 171 which supports pivot rods 172 for the links 173 which in turn are connected by pivots 174 with the upper ends of the needle valves 154a, 154b, 154c and 154d. This valve actuating member 171 is constructed as shown in Figure 11, of sheet metal folded to provide four spaced parallel legs 171a, the gap between the two center legs being closed by a piece 171b welded thereto, and the free ends of the original strip are likewise joined by welding, so that a strong composite structure is produced. The outer walls are closely received between the straps 142, while the portions of lever 52 fit just outside the two inner walls, and the links 173 are received between the two inner walls. Extending through apertures of all these walls is the supporting pivot 176 which preferably has an upward extension 177 for limiting axial movement. The apertures through which the pivot 176 passes, in the walls 171a, are oblong, with their major axes in the plane through the axis of pivot 170. This permits movement of the member 171 relative to this supporting pin 176, for self-adjustment.

45 Further, the pivots 174 (Fig. 10) at the lower end of each link 176 preferably pass through apertures in links 173 which are bellied-out at each end, whereby the pins 174 may rock, and thus assure correct seating of the corresponding valves 154b, 154c, 154a and 154d; and thus compensate for irregularities of length in such valves.

50 The lever 52 is so connected to member 171 by pivot 170 that a slight downward counter-clockwise rocking movement of the lever arm 52 is permitted before it engages the left hand upper surfaces (Fig. 4) of member 171, and the connecting wall 52b likewise can make a slight clockwise movement with lever 52 relatively about pivot 170 before it encounters member 171.

60 It will be noted that the several passages may be formed easily by drilling in the body 143, and then closed by corresponding plugs 158x, 159x, 161x (Figs. 7, 8 and 9).

65 In operation, when the parts are in the position of Figure 1a, compressed gas is entering past the open inlet valve 45, and by its action upon the body of liquid in casing 19 is forcing this liquid therefrom and through the check valve 85 and pipe 78. At this time the exhaust valve 32 is closed, piston rod 37 is in its raised position, gas inlet needle valve 154a is open while gas inlet needle valve 154c is closed, exhaust valve 154d is open while exhaust valve 154b is closed, so that the lower end of the cylinder 144 has been receiving gas under pressure from pipe 61, while

the upper end has been exhausting through pipes 59, 59a. The servo motor actuating link 53, 53b is in raised position and lever 52 is in its extreme clockwise position of movement, and the toggle devices 52a, 166 have been displaced to the right 5 from the central position of Fig. 4, so that these devices are holding the valves in such positions.

As the forcing of liquid from housing 19 continues, the float 71 descends and comes to rest on the bumper 81a, and finally, as the liquid level 10 falls below the top of the shield 75, the bucket 74 begins to sink and by its engagement with lever 69 causes a downward movement of the servo motor control link 53, 53b, and thus a counter-clockwise movement of lever 52. At first, this 15 movement causes a rocking of valve actuating member 171 to close the open valves 154a, 154d under the action of spring 165 as the toggle devices swing toward central position, this closing being permitted by the oblong hole for pivot 176. 20 In the course of this movement, however, the knife edge 163 is moved past the line of centers between the point 166a and the axis of pivot 170, so that the energy which has been stored in spring 165 during this initial movement is now 25 released and cooperates with the downward pull of link 53, 53b, to cause a further movement of lever 52 and therewith a tilting of the valve actuating member 171 which assures the complete closing of valves 154b and 154c and the opening 30 of valves 154a and 154d. Thus, the connections to the cylinder are reversed, so that the lower end of the cylinder is permitted to exhaust while compressed gas is delivered to the upper end. The piston and its rod 37 are thus moved downward and cause a reversal of the main valves 32 and 43, thus shutting off the inflow of compressed gas into the housing 19, and permitting the latter to exhaust to conduit 26, 26a. Liquid then enters through pipe 12 and past check valve 94, 40 raising the bucket 74 so that lever 69 is free and ultimately raising the float 71 and operating lever 54 to reverse the aforesaid actuation of lever 52 and thus return the parts to the initial position. Compressed gas now flows from pipe 61 45 and passage 161 to the lower end of the cylinder, while the upper end is permitted to exhaust. Thus the servo motor returns the valves 32 and 45 to the position shown in Figure 1a, and the device is returned to its former position. 50

The structure thus comprises a casing which may be placed in communication with a compressed gas conduit or with an exhaust conduit by the operation of the main valves 45, 32. This operation is secured by a servo motor structure 55 comprising a cylinder and piston, and itself controlled through the agency of the four reciprocating valves which selectively control the opening and closing of passages leading to the cylinder ends, with respect to compressed gas and exhaust conduits 61, 59, etc. These valves are controlled by a rocker piece which is in effect a walking beam connected at its ends to the valves, but capable of a vertical bodily movement by reason of the provision of its slots for reception of the 65 pivot 176. The crank lever 52, 52a is pivoted to this rocker piece, but has a certain free movement with respect thereto, so that it accomplishes a positive movement of the rocker piece, which has a limited free movement when its 70 own motion is reversed. This lever is associated in a toggle system whereby the toggle spring is employed to force the lever and the rocker piece downwardly, and therewith secure a seating of all valves, while the toggle spring 75

is also available for its normal toggle link purpose of moving the lever toward its end positions and holding it therein, with two of the valves raised and the other two closed. This lever is actuated by the float and bucket which thus constitute means responsive to the liquid level prevailing within the casing. A further feature of the arrangement is that the rocker piece permits differential downward movements of the two valves which are located at each end thereof (Fig. 10), so that the seating of these valves is assured under the action of the aforesaid spring pressure, even though the length of each valve is not identical with the length required for accurate closing during the downward movement of the rocker piece.

The violent gas and liquid currents within the housing tend to move the levers 52 and 54 before the true actuation by the bucket has occurred. For this purpose, baffles 190, 191 are provided above these levers, whereby to avoid such injurious actuation.

It is obvious that the invention is not limited to the form of construction shown, but that it may be modified within many ways of the scope of the appended claims.

Having thus described the invention, what I claim as new and desire to secure by Letters Patent, is:—

1. In a device of the class described, a valve actuator, supporting means for said actuator, reciprocable inlet and outlet valves, said valve actuator having pivot connections to each of said valves, a control lever pivoted to the actuator between the valve pivot independently of said supporting means, means on said lever and actuator for causing positive movement of the actuator by said lever upon motion of the latter in either direction and affording a limited free movement of the lever upon reversal of its direction of movement, and a spring for pressing said lever toward said actuator.

2. A device as in claim 1, including fixed pivot means engaged with said actuator for preventing bodily movement of the actuator during the free movement of the lever.

3. A device as in claim 1, in which said actuator is movable in the direction of valve movement and said spring is included in a toggle link cooperative with said lever actuator and valves for moving all the valves toward closed position and cooperating with said lever to cause movement of the lever toward its end positions and operating to hold the lever in such end position with one valve open and the other closed and also operating to move the actuator and valves bodily toward closed position of the valves.

4. In a device of the class described, a frame, a rocker piece; a toggle including a spring, a first toggle link pivotally connected to said piece,

a second toggle link cooperative with said first toggle link and having pivotal engagement with said frame; a pair of rectilinearly movable valve means connected to said rocker piece at opposite sides of the axial plane of said frame pivot engagement which intersects the point of said pivotal connection, a loose pivotal connection between said piece and the frame spaced from said toggle pivot connection and operative for preventing lateral bodily movement of the piece and permitting bodily movement toward and from the point of pivotal engagement of said second toggle link for assuring the seating of at least one said valve means at all times and of both said valve means in the course of the movement of the rocker piece, and means for rocking said first toggle link.

5. A device as in claim 4, in which each valve means includes a pair of valves and means for pivotally connecting the same to said rocker piece, said pivotally connecting means including loose connections cooperating with said loose pivotal connections for assuring the seating of both valves of a pair by the action of said toggle spring.

6. In a device of the class described, four substantially parallel passages arranged at the corners of a rectangular cross section, inlet and outlet conduits extending across the diagonals of said section and each communicating with two of said passages, valves for closing the communication between said conduits and passages, a walking beam rocker-piece, said valves being connected to the ends of the walking beam rocker-piece, and spring means cooperative with said rocker-piece for holding said valves closed when said walking beam is in center position and for causing rocking of said walking beam about either end for effecting an opening of the valves connected at the other end thereof.

7. A device as in claim 6, in which the rocker-piece has a slot therein and a pivot member on said frame passes through the slot, said pivot and the walls of the slot operating to prevent bodily movement of the rocker-piece in the plane of the valve connection.

8. In a device of the class described, a rocker-piece, means providing an axis about which the piece may turn a transverse pin extending through an aperture of the rocker-piece located at a point spaced from the said axis, reciprocable valves having apertures for the reception of said pin, said apertures having a greater cross sectional area for at least a portion of their length than the cross sectional area of the pin, whereby the pin may rock within said rocker-piece and valves so that a downward movement of the rocker-piece at said pin will produce a positive closing of both said valves.

CHARLES A. BUTLER.
